United States Patent Office.

WILLIAM A. BRADFORD, OF CINCINNATI, OHIO, ASSIGNOR TO C. G. PEASE,
TRUSTEE FOR MALONE SAFETY-VALVE COMPANY.

Letters Patent No. 98,019, dated December 21, 1869.

IMPROVEMENT IN LOW-WATER INDICATORS.

The Schedule referred to in these Letters Patent and making part of the same

To all whom it may concern:

Be it known that I, WILLIAM A. BRADFORD, of Cincinnati, in the county of Hamilton, and State of Ohio, have invented a certain new and useful Improvement in Low-Water Indicators; and I do hereby declare that the following is a full, clear, and exact description of the construction and operation of the same, reference being had to the annexed drawing, making part of this specification, which is an axial section, partly in elevation, of an apparatus embodying my invention, attached to a steam-boiler.

My invention relates to that class of low-water indicators which embodies a stationary pendent valve, adjustable in position, surrounded by a tube, which is fitted at its upper end with an alarm-whistle and valve-seat, the seat being elevated off the valve in order to sound the alarm, by the expansion of the tube when occupied by steam, and depressed so as to close the valve by the contraction of the tube when occupied by water, the lower end of the expansion-tube being situated at or near the water-line of the boiler; and

My invention consists of a peculiar construction of the pendent valve-stem and its connections, by which the valve is not only rendered adjustable, but is locked or fastened rigidly by the same device at any required point of adjustment.

A is a pipe connecting the indicating-mechanism with the boiler.

It passes through aperture C C, in the periphery of the boiler, which is large enough to permit steam to pass around the said pipe A into the safety-valve B.

The pipe L connects with the pipe A, as shown.

D D are rods, secured firmly by the nuts M M to the plates E and E', both above and below said plates. The plate E is permanently attached to the framework, as shown, and the purpose of the plate E; rods D D, and nuts M M, is to hold the plate E' securely in place, as shown.

K is a tube passing through the whistle P.

I is a stem, passing through and fitting neatly in the tube K, in which it is intended to slide when the expansion hereinafter referred to takes place.

The stem I has a screw-thread chased upon its upper end, and is provided with adjusting-nuts N N, one on each side of the stationary bar E, through which the valve-stem passes.

The valve is adjusted by means of the nuts N, and by the same means is locked or rigidly secured at any point of adjustment, in such a secure manner that the valve cannot be forced up or down without the aid of a wrench, or be liable to alteration or displacement by meddlesome persons.

H' is an inverted valve, the conical sides of which

fit steam-tight against its seat H. Said valve H is permanently fixed to the foot of the stem I.

P' P is a circular aperture, through which the steam passes when it escapes, and thence comes into contact with the whistle P.

R is an ordinary globe-valve.

O is a lock or case to be locked, which is intended to secure the parts above shown from the control of the engineer.

S is a pipe, which is a continuation of the pipe A, and which is regulated by the globe-valve T, and through which it is intended to take the water from the boiler for the extinguishment of accidental fires.

The operation of the low-water indicator herein shown, of which my invention forms a part, is as follows:

The lower end of the pipe A is to be placed in such position in the boiler, below which the water should never be permitted to go.

When the water in the boiler gets lower than the mouth of the pipe A, steam will rise through it into the pipe L, and will, in a very short time, expand said pipe L, the result of which will be that the seat H of the stationary valve H' will be raised from the valve, when the steam will escape between the seat and the valve, and thence out through the circular opening P', where it will come in contact with the edge of the whistle P, and give the low-water alarm.

Of course it will be understood that the globe-valve T is shut, and the globe-valve R is open, during the operation just described.

The provision of the screw-threaded valve-stem I and nuts N N gives the means for the necessary adjustment of the valve H', and is of such a character that when once adjusted and locked by the said nuts N, alteration or displacement by unauthorized persons is difficult and not likely to occur, and in this respect differs from existing devices for the adjustment of the valve H'.

Having thus described my invention,

What I claim as new, and desire to secure by Letters Patent, is—

In combination with the expansion-tube L, fitted with a steam-whistle, P, and valve-seat H, the pendent stationary valve H', when said valve has a screw-threaded stem, I, and adjusting-nuts N N, arranged and operating in the manner and for the purpose specified.

W. A. BRADFORD.
